UNITED STATES PATENT OFFICE

2,588,167

STRIKER FOR IGNITERS

Conrad David Schermuly, Alfred James Schermuly, and Charles Schermuly, Parkgate, Newdigate, England

Application September 4, 1946, Serial No. 694,683
In Great Britain February 23, 1945

4 Claims. (Cl. 42—69)

1
This invention relates to strikers for igniters of the kind wherein the striker pin is held in its retracted position against a spring by means of a pin or slotted plate either of which, when withdrawn, allows the striker to move onto an explosive cap to detonate it.

Hitherto it has been usual, in order to release the striker, to remove the pin by holding the device in one hand and removing the pin or slotted plate with the other. In this manner the device at the instant of firing is held in only one hand, and it has been found that with some devices, notably those which, when fired, have substantial recoil, it is desirable that the device should be held with both hands.

The principal object of the present invention is to provide means whereby the device can be held with both hands at the same time, the striker being operated without removing either hand.

The invention will now be described with reference to the accompanying drawings which show one embodiment of the invention wherein:

Figure 1 is a longitudinal section through a device comprising a striker,

Figure 2 is an end elevation, viewed from the right in Figure 1, of the device with the handle removed and

Figure 3 is an end elevation, viewed from the left in Figure 1, of the handle.

Referring to the drawings, the striker 1 has one end 2 flattened and formed with a shoulder 3. The other end of the striker 1 is provided with a point 4 adapted to strike a detonating cap. The striker 1 and its associated spring 6 are carried in a sleeve 7 one end of which is provided with a recess 5 for the detonating cap and the other end of which is secured to a plate 8. The plate 8 is circular and is provided with a central aperture 9 through which the end 2 of the striker 1 passes. The sleeve 7 is rigidly held in the rear end of a barrel portion 10, which may be a part of, or may be secured to, a discharger for rockets or the like.

From Figure 2 it can be seen that the aperture 9 is of elongated shape so that when the striker is turned to bring the flattened end 2 into coincidence with the aperture 9, the spring 6 can force the striker 1 forward to detonate the cap in the recess 5. On the other hand, when the end 2 is turned through 90° into the position shown in Figures 1 and 2, the shoulder 3 of the end 2 abuts against the plate 8 and holds the striker 1 in retracted position.

Turning of the striker 1 is effected by means

2
of a handle 11 having at its front end a portion 12 of reduced diameter adapted to slide within the rear end of the barrel portion 10. The portion 12 has in its face a recess 13 which is the same shape as, and slightly larger than, the end 2 (see Figure 3). By holding the barrel portion 10 in one hand and gripping the handle 11 in the other hand, the barrel portion may be held firmly while the handle 11 is turned through 90°. Such turning releases the striker 1 and fires the detonating cap.

To render impossible any premature actuation of the striker 1, the rear end of the barrel portion 10 and the portion 12 of the handle 11 may be bored for the reception of a safety pin 14.

What we claim is:

1. A device comprising a barrel portion, a spring loaded striker in said barrel portion, a portion of said striker being of flattened cross-sectional shape and extending longitudinally axially at the rear end of said striker with a shoulder on the front end of said flattened portion, an apertured plate across the said barrel portion adjacent the rear end thereof at right angles to the longitudinal axis of the striker, said plate having an elongated aperture of the same shape as and slightly larger than the cross-section of said flattened portion of the striker, said striker being rotatable relative to the plate, said handle rotatable about its axis on the rear end of said barrel portion adapted to engage with said striker whereby said aperture may be aligned with the flattened portion of said striker, thus permitting free movement of said striker axially of said barrel.

2. A device comprising a barrel portion, a rotatable striker movable in said barrel portion, a spring urging the striker forward, an apertured fixed plate across the barrel adjacent its rear end at right angles to the longitudinal axis of the striker, said plate having an elongated aperture, a rear axially extending portion of the striker being of flattened cross-sectional shape substantially the same as and slightly smaller than the elongated aperture and having a shoulder at its front end, whereby the striker may be held in retracted position by passing said flattened portion through said elongated aperture and turning said striker so that said shoulder abuts against said plate, a rotatable handle on the rear end of said barrel portion, said handle having a common axis with the striker and being rotatable around its axis, a front face of said handle having a recess of cross-sectional shape similar to but slightly

larger than said flattened portion and adapted to receive said flattened portion, whereby by turning said handle about its axis the said flattened portion may be turned to a position where it is coincident with said elongated aperture in

5

which position said spring can move said striker forward.

3. A device as claimed in claim 2 wherein the rear end of said barrel portion, and said handle are apertured to receive a safety pin.

10

4. A device as claimed in claim 2, wherein a sleeve in said barrel portion houses said striker.
